(57) CLAIM

The ornamental design for a keepsake wall hanging, as shown and described.

DESCRIPTION

FIG. 1 is a perspective view of a keepsake wall hanging showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a bottom plan view thereof;

FIG. 7 is a top plan view thereof; and,

FIG. 8 is an additional perspective view thereof, with the ribbons shown untied and the broken-line disclosure of a rod in the views being for illustrative purposes only and forming no part of the claimed design.
